(57) **CLAIM**

The ornamental design for a cushion clip for a respiratory mask, as shown and described.

DESCRIPTION

FIG. 1 is a front perspective view of a cushion clip for a respiratory mask according to our design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear perspective view thereof;

The broken line showing in FIG. 9 is to illustrate environment only and forms no part of the claimed design.
